TOBACCO STICK HOLDER AND STICK FEEDER

Thomas B. Kreeger, Pfafftown, N. C.

Application June 30, 1947, Serial No. 758,082

4 Claims. (Cl. 214—5.5)

1

My invention relates to improvement in tobacco stick holders and feeders for use in loading such sticks with tobacco leaves.

As explanatory, it is the usual practice to load so-called tobacco sticks with tobacco leaves by tying the green leaves to the sticks in clusters spaced along the same, the sticks being then used for hanging the green tobacco leaves in a curing barn, or the like, for curing. The tobacco sticks are held horizontally in holders, usually, and the loading or tying is done by an operator standing up before the sticks and moving along the same to space the tying properly. This is laborious, fatiguing and time-consuming.

With the foregoing in mind, it is the primary object of my invention to provide a simple form of device for holding such tobacco sticks by one end and feeding the same away from an operator seated, so that the tobacco leaves may be tied to and spaced along the sticks by the seated operator; whereby the loading of such sticks may be accomplished quickly and easily and with a minimum amount of labor.

Another object is to provide a device of the character and for the purpose above set forth which is adapted for use by either right- or left-handed operators.

Still another object is to provide a tobacco stick holder and feeder which will not readily get out of order, is easy to move about, as required, and comparatively inexpensive to manufacture.

Other and subordinate objects also comprehended by my invention, together with the precise nature of my improvements, and the advantages thereof will be readily understood when the succeeding description and claims are read with reference to the drawings accompanying and forming a part of this specification.

In the drawings:

Figure 1 is a view in side elevation, partly broken away, and illustrating my improved tobacco stick holder and feeder in a preferred embodiment thereof, the parts being shown in normal position;

Figure 2 is a similar view illustrating the tobacco stick holder feeding bars with the tobacco stick holder swung into the limit of movement thereof in one direction, and the seat post lowered to move the long lever arm of the lever bar upwardly for such swinging of said feeding bars;

Figure 3 is a view in plan with the parts shown in normal position;

Figure 4 is a fragmentary view in longitudinal section taken on the line 4—4 of Figure 3;

Figure 5 is a view in vertical transverse section

2

taken on the regular line 5—5 of Figure 1; and Figure 6 is a similar view taken on the line 6—6 of Figure 1.

Referring now to the drawings by numerals, 5 my improved tobacco stick holder and feeder, in the illustrated preferred embodiment thereof, comprises a base frame 1 embodying a pair of side by side, horizontal beams 2 supported at the ends thereof by pairs of subjacent cross bars 3 10 on which said beams 2 are secured, in any suitable manner, in laterally spaced, parallel relation, and which form downwardly and outwardly inclined supporting and stabilizing legs for said frame. The beams 2 and bars 3 may be formed 15 of any suitable, relatively light, strong material such as wood.

A tubular seat post guide 4 arises from one end of the frame 1 with a base flange 5 suitably secured to the beams 2 at one end thereof so that 20 said guide 4 is vertically aligned with the space between said beams 2.

A seat post 6 extends downwardly through the seat post guide 4 into the space between said beams 2 with a preferably rectangular seat panel 25 7 on the upper end thereof suitably attached adjacent one end of said panel on top of said post so that the seat panel 7 may extend endwise from said post 6 well beyond one side of the frame 1 for a purpose presently seen. The seat post 6 is 30 vertically movable and rotatable in the seat post guide 4 for a purpose to be explained.

A lever bar 8 is pivoted, intermediate its ends, as at 9, to extend horizontally in the space between the beams 2 and rock vertically, the pivot 9 being arranged to provide a short lever arm 10 on said bar 8 on the end of which the seat post 6 rests, and a long lever arm 11 on said bar 8 adapted to be rocked upwardly by the weight of an operator seated on the seat panel 7.

40 A leaf spring 12 overlies the long lever arm 11 of the lever bar 8 with one end fixed, as at 13, to the beams 2 and tensions said lever arm 11 against being rocked upwardly. A set screw 14 threaded into a cross cleat 15 on said beams 2 is provided 45 for turning against said spring 12 to vary the tension exerted against said lever arm 11.

A pair of upstanding stick holder feeding bars 16, 17 at the end of the frame 1 opposite the seat-equipped end, are pivoted, as at 18, 19, at the 50 lower ends thereof between the beams 2, adjacent the long lever arm 11, to be swung side by side in spaced apart relation in the plane of the frame 1 toward and from the seat panel 7.

55 A stick holder 20 pivotally connects the upper ends of said feeding bars 16, 17. The stick holder

20 comprises an elongated plate 21 extending endwise, horizontally, across the upper ends of said feeding bars 16, 17 and pivoted adjacent opposite ends thereof to one side of said bars, as at 22, 23 so that said bars 16, 17 form a parallel link motion and maintain said holder 20 horizontal. An upstanding, forked stick rest 24 on one end of said plate 21 faces the seat-equipped end of the frame 1. An upstanding stick grip 25 on the other end of said plate 21 curves toward said rest 24 with a downwardly curving and opening end fork 26 adapted to straddle and frictionally grip one end of a tobacco stick 27 disposed horizontally in said rest 24 with its major portion extending from said rest toward and over the seat panel 7 and overbalancing said stick 27 on said rest 24 to force said end of the stick into said fork 26.

An abutment block 28 on the feeding bar 16 overlies the end of the long lever arm 11 of the lever bar 8 and is secured to said bar 16 by bolts 29, the arrangement being such that when said lever arm 11 is moved upwardly, the end of the lever arm slidably engages said block 28 and thereby swings the stick holder feeding bars 16, 17 away from the seat panel 7 from a normal position. A suitably arranged coil spring 30 tensions the stick holder feeding bars 16, 17 so as to swing into a normal position in which the same incline upwardly toward the seat panel 7 above the same.

A suitable twine holder 31 is provided on the seat-equipped end of the frame 1 to hold a ball of twine within easy reach from the seat panel 7. In using the described invention, the operator, not shown, positions one end of the tobacco stick 27 into the tobacco stick holder 20 in the manner described and with the tobacco stick holder 20, and said feeding bars 16, 17 in the described normal position shown in Figures 1 and 4. In this connection, it is to be explained that said feeding bars 16, 17 in the normal position thereof hold the end of the tobacco stick 27 in said holder 20 within reach of an operator occupying the seat panel 7. The operator now mounts the seat panel 7 astride the same and facing one side or the other of the frame 1, depending on whether he or she is right or left handed, so that the tobacco stick 27 extends across the operator's lap. In this connection, it will be noted that the seat post 6 being rotatable in the seat post guide 4, the seat panel 7 may be turned to extend outwardly of either side of the frame 1 so that a seated operator may have the tobacco stick 27 crosswise of his or her lap when facing either side of the frame 1. When seated, the operator may hold onto the tobacco stick 27 so as to prevent his weight from operating the lever bar 8, and consequently the tobacco holder feeding bars 16, 17, in a manner which will be clear. By tying the tobacco leaves, not shown, along said stick 27, beginning adjacent said holder 20, and alternately releasing and gripping said stick 27, the weight of the operator may be utilized to lower the seat post 6 and thereby cause the lever bar 8 to be rocked so as to intermittently move the long lever arm 11 upwardly and swing the tobacco stick holder feeding bars 16, 17 away from the operator, step by step, until the tobacco stick 27 is fully loaded. Then the operator may remove the loaded tobacco stick 27, in a manner which will be understood, and arise from the seat panel 7 to permit the coil spring 30 to return the tobacco stick holder feeding bars 16, 17, together with said holder 20, back to normal position, the leaf spring 12, in the meantime, returning the lever bar 8 and the seat post 6 and seat panel 7 to normal position. Then the

operations described may be repeated. As shown in Figure 2, a suitable stop 31 on the frame 1 is provided for limiting swing of the tobacco stick holder feeding bars 16, 17 away from the operator. The tension exerted by the leaf spring 12 may be regulated in accordance with the weight of the operator, by means of the set screw 14, so that such weight will cause upward movement of the long lever arm 11 of the lever bar 8 to operate the tobacco stick holder feeding bars 16, 17 in the manner described.

The foregoing will, it is believed, suffice to impart a clear understanding of my invention, without further explanation.

Manifestly, the invention as described is susceptible of modification without departing from the inventive concept and within the scope of the appended claims.

Having described my invention, what is claimed as new is:

1. In a device of the class described, a base frame, a seat for an operator, means to mount said seat on said frame for downward movement under the weight of the operator seated on the seat, a holder adapted to grip one end of a tobacco stick and hold the same in horizontal position with said stick extending across said seat and the lap of the operator when seated on the seat, supporting means for said holder movable on said frame to move said holder away from said seat for correspondingly moving the stick relative to the operator seated on the seat, and means on said frame operative by the seat in its downward movement to engage said supporting means and move the same, said supporting means comprising parallel links pivoted on said frame for maintaining said holder horizontal together with said stick.

2. In a device of the class described, a base frame, a seat for an operator and including a seat post, means to mount said seat post on said frame for downward movement under the weight of the operator seated on the seat, a holder adapted to grip one end of a tobacco stick and hold the same in horizontal position with said stick extending across said seat and the lap of the operator when seated on the seat, supporting means for said holder movable on said frame to move said holder away from said seat for correspondingly moving the stick relative to the operator seated on the seat, and means on said frame operative by the seat post in its downward movement to engage said supporting means and move the same comprising a lever bar pivoted on said frame for vertical swinging, said seat post resting on one end of said lever bar.

3. In a device of the class described, a base frame, a seat for an operator and including a seat post, means to mount said seat post on said frame for downward movement under the weight of the operator seated on the seat, a holder adapted to grip one end of a tobacco stick and hold the same in horizontal position with said stick extending across said seat and the lap of the operator when seated on the seat, supporting means for said holder movable on said frame to move said holder away from said seat for correspondingly moving the stick relative to the operator seated on the seat, means on said frame operative by the seat post in its downward movement to engage said supporting means and move the same comprising a lever bar pivoted on said frame for vertical swinging, said seat post resting on one end of said lever bar, and spring means on said frame for opposing swinging of said lever bar in

accordance with the weight of the operator seated on the seat.

4. In a device of the class described, a base frame, a seat for an operator, means to mount said seat on said frame for downward movement under the weight of the operator seated on the seat, a holder adapted to grip one end of a tobacco stick and hold the same in horizontal position with said stick extending across said seat and the lap of the operator when seated on the seat, supporting means for said holder movable on said frame to move said holder away from said seat for correspondingly moving the stick relative to the operator seated on the seat, and means on said frame operative by the seat in its 15 downward movement to engage said supporting

means and move the same, said holder comprising a forked grip for straddling and frictionally gripping said stick, and a forked rest for fulcruming of the stick therein to swing said stick into said forked grip.
